UNITED STATES PATENT OFFICE.

MICHAEL SANDFIELD, OF WILKINSBURG, PENNSYLVANIA, ASSIGNOR TO WESTINGHOUSE ELECTRIC AND MANUFACTURING COMPANY, A CORPORATION OF PENNSYLVANIA.

COIL-FORMING APPARATUS.

1,153,344.

Specification of Letters Patent. Patented Sept. 14, 1915.

Application filed February 1, 1912. Serial No. 674,805.

To all whom it may concern:

Be it known that I, MICHAEL SANDFIELD, a citizen of the United States, and a resident of Wilkinsburg, in the county of Allegheny and State of Pennsylvania, have invented a new and useful Improvement in Coil-Forming Apparatus, of which the following is a specification.

My invention relates to machines for forming coils to be used in dynamo-electric machines and it has for its object to provide a simple, durable and effective mechanism whereby a coil blank of an elongated form and having all of its turns in the same plane may be bent into a skewed diamond form for application to the slots of a cylindrically curved core by two simple movements of the operating parts and whereby the operation may be repeated upon any number of successive duplicate coil blanks with the certainty of producing finished coils of exactly the same form and dimensions.

In my co-pending application, Serial No. 598,520, filed December 21, 1910, assigned to the Westinghouse Electric and Manufacturing Company and patented Sept. 10, 1912, as No. 1,037,998, I have shown and described a coil-forming machine of the same general character as that constituting the subject-matter of my present invention, the latter embodying novel features and being equipped with additional mechanism which co-operates with the other parts of the apparatus to produce a skewed coil instead of a symmetrical coil of the diamond type.

Figure 1 of the accompanying drawings is a front elevation of a coil-forming machine constructed in accordance with my invention and showing a coil blank in position. Fig. 2 is a side elevation of the apparatus shown in Fig. 1, the movable member of the apparatus being shown in open position and the coil in a form adapted for use. Fig. 3 is a plan view of a completed coil. Figs. 4, 5 and 6 are, respectively, a sectional view, a plan view and an end elevation, on a larger scale, of the coil-forming mechanism which is mounted on the movable member of the apparatus shown in Figs. 1 and 2 and comprises relatively adjustable parts for the purpose of offsetting one side of the coil relative to the other side, as hereinafter more fully pointed out.

The frame upon which the operating mechanism of the apparatus is mounted is preferably disposed in a substantially vertical plane, and comprises standards 2 and a vertical channel plate 3 provided with a slot 4 and with a graduated scale 5 upon its front face. A casting 6, which is provided with projections 7, is bolted to the lower end of the channel plate 3, and a horizontal shaft 8, having a longitudinal groove 9 in its upper side, extends through and is rigidly secured to the projections 7. A lever 10, having a longitudinal slot 11 in its upper portion and a transverse slot 12 at its extreme upper end, to provide a handle, has two curved portions 13 and 14 below the longitudinal slot 11, and its lower end is provided with a weight 15. Between the two curved portions 13 and 14, the lever is provided with a bearing to receive the shaft 8, so that a rotative movement of the lever 10, relative to the shaft is permitted.

Each end of the shaft 8 is provided with an adjustable block 16 loosely mounted on a sleeve or bushing 16^a having a spline 17, which fits into the groove 9 in the shaft 8. The sleeve is readily movable longitudinally of the shaft except when the spline is pressed into the groove by means of a curved rod 18, the horizontal portion of which serves as a handle and the vertical portion of which may be screwed into the sleeve, so that its inner end will bear against the spline. The block 16 is free to rotate about the sleeve 16^a, but its position is otherwise determined by the sleeve. Mounted upon the block 16, is a U-shaped frame 19 having slots 20 to receive a bolt 21 to which the block is connected by a link 21^a and an eccentric 22^a, the frame being vertically adjustable to the limit of the length of the slots and being clamped in any position to which it may be adjusted, by means of the bolt 21 and its nut. The head of the bolt 21 is provided with a bent rod projection 23^a which constitutes a handle lever by which the bolt and the eccentric 22^a may be rotatively moved for the purpose of temporarily raising or lowering the clamps 63 at the time the coil blank is secured in position, as hereinafter pointed out. The frame 19 is constrained and guided in fixed relation to the block 16 by means of ribs 19^a formed on the opposite inner sides of the frame 19.

and slidably coöperating with corresponding grooves in the blocks 16.

The shaft 8 is provided with a graduated scale in order that the degree of longitudinal adjustment of the blocks may be accurately determined. The lower ends of two rods 23 and 24 are pivotally attached to each frame 19, such lower ends being of U-shape (see Fig. 2) and of such dimensions as to receive the upper end of the frame 19 between the arms of the U-shaped portions.

The arrangement of the rods 23 and 24 is such that a clamp 63 is maintained horizontal, thereby avoiding friction between the parts and the coil ends during the forming process. This is particularly important, since the insulation on the coil would otherwise be injured.

The casting 6 is provided with a sector 20 25, having a graduated scale and with teeth corresponding to the scale graduations, which are intended to indicate the angular movement of the lever 10 relative to the channel plate 3.

25 Mounted upon the sector 25 is a stop block 27 having a clamping screw 28, so that it may be adjusted to any desired position on the sector and securely locked in that position with its upper face coinciding with 30 any one of the scale graduations. The curved portion 13 of the lever 10 is provided with a portion 29 which embraces the sector 25 and is adapted to engage the stop block 27 and thus limit its degree of movement to such extent as may be desired. A latch 29^a is pivotally secured to the portion 29 and is adapted to engage the lower edge of the stop block 27, thereby locking the lever in position after the coil blank is 40 spread.

A casting 30 is mounted upon the channel plate 3 and is so clamped in position thereon, by means of a bolt 31 and the slot 4, as to be adjustable vertically in accordance 45 with the radius of the core member for which the coil to be bent is intended, the degree of adjustment being determined by means of the graduated scale 5. The casting 30 constitutes one member of a clamp 50 and is provided with a seat 32 for one side of the coil to be bent, the other member 33 of the clamp being hinged to the lower edge of the casting and having a seat 34 which is the counterpart of the seat 32 in the casting. 55 The hinged member 33 of the clamp is connected to an eccentric 35, by means of a link 36, and the eccentric is turned, to open and close the clamp, by means of a rod or lever 37.

60 Referring specially to Figs. 4, 5 and 6, a casting 38, which corresponds to the casting 30, is mounted on a carriage 39 having strips or guide rails 40 and 41 between which a portion 42 of the casting 38 projects and on 65 which the casting may be adjusted trans-

versely of the lever 10. The casting 38 is held in position by hooked flanges 43 and 44 with which the rails 40 and 41 are provided. The carriage 39 is pivotally secured to a casting 45 by means of a pin 47, the casting being mounted upon the lever 10 and being clamped thereto by means of a bolt 46. The adjustment of the carriage 39 about the pin 47 is limited to a very small angle by a bolt 48 which extends through a curved slot 49 in a projection 50 of the casting 45 and which is secured, at its ends, to lugs 51 with which the carriage 39 is provided. An adjusting screw 52 is rotatively mounted in side members 53 of the carriage 39. A nut 54 is mounted on the adjusting screw 52 between the side members 53 and is provided with a projection 55 which extends into the casting 38, the arrangement of parts being such that the rotation of the screw 52 produces an adjustment of the casting 38 on the carriage 39 transversely of the lever 10.

In order to facilitate the rotative movement of the adjusting screw 52, a handle 90 lever 56 is provided, as shown in Figs. 4, 5 and 6 of the drawings.

The casting 38 is provided with a seat 57 for one side of the coil blank, and a clamp member 58 is hinged to the upper edge of the casting, its lower edge being provided with a seat 59 which is the counterpart of that in the casting. The hinged clamp member is connected to an eccentric 60 by means of a link 61, and the eccentric is turned to open and close the clamp by means of a rod or lever 62, this clamping structure being substantially like that which is mounted on the channel plate.

Each pair of rods 23 and 24 is provided with a clamp 63 for one end of the coil blank, this clamp comprising a block 64 having slots 65 and bearing pieces 66 therein for the rods 23 and 24 which are so disposed as to permit freedom of relative movement between the rods and the block. Clamped to the inner end of the block are two plates 67 having front edges of such form as to receive the coil ends and, in a measure, to determine the form which such ends shall take when the bending is completed. A rod 68 of approximately L-shape has its longer arm projecting through a hole in the plates 67 and the end of the block 64 and is provided with nuts to prevent its accidental withdrawal, and its shorter arm fits into holes in the ends of the plates and also in the end of the opening between the sides of the coil blank so as to hold the coil blank in position while it is undergoing the bending operation. (See Fig. 2.) The two sets of rods and the coöperating clamps are similar and, consequently, a description of one will suffice for both.

In using the apparatus to bend a coil into

final form, the sides of the coil blank having the form indicated in Fig. 1 are clamped in the seats 32 and 34, and 57 and 59 by means of the eccentrics 35 and 60 and the levers 37 and 62. The end clamps 63 are brought into position, the frames 19 being first either lowered into the position of Fig. 1 by turning the handle levers 23^a, or raised into its opposite position according as the coil is to be used on the stator or the rotor of a dynamo-electric machine, with the ends of the coil blank projecting into the spaces between the plates 67, and then the L-shaped rods 68 are inserted. The handle of the lever 10 is grasped by the operator and is drawn away from the frame until its part 29 engages the stop 27 which has been set in accordance with the desired width of the coil. The frames 19 are either raised or lowered from their original setting by turning the handle levers 23^a according as the coil is to be used on the stator or the rotor of a dynamo-electric machine. This operation shapes the coil for fitting into slots formed either on the stator or rotor, as required. When the frames 19 are in the raised position, the parts of my machine at the end of the complete operation, are positioned as indicated in Fig. 2. At this stage of the bending process, the coil is a regular diamond shape, the two side portions which are adapted to enter the core slots of the dynamo-electric machine being directly opposite each other. In order to produce the skewed diamond shape as shown in Fig. 3 of the drawings, the adjusting screw 52 is so rotated as to move the coil clamp comprising the parts 38 and 58 on the guide rails 40 and 41 and to force the side of the coil, which is gripped in this clamp to one side, making it offset relative to the side which is held in the clamp comprising parts 32 and 34. The L-shaped rods 68 may now be removed and the coil be released from the clamps, when it may be readily removed and the parts returned to the original position for the insertion of another coil blank. The operation may be repeated any desired number of times with the certainty that the resulting coils will be alike in form and dimensions, provided the original blanks are alike.

The adjustment features provided and hereinbefore described, are obviously such as to permit adaptation of the apparatus to coils of various sizes which are intended for use with either stationary or rotatable core members of various diameters, the blocks 16 being adjusted upon the shaft 8 to such positions that, when the lever 10 is in its outermost position and the coil is bent to its final form, the rods 23 and 24 will be substantially at right angles to the shaft 8. The end clamps 63 are adjusted upon the rods 23 and 24 to such position that the coil

ends will be offset, relative to the imaginary surface generated by the sides of the coil as they are separated in the forming process.

When the coils are intended for insertion in slots in the concave surface of the stator core of an induction motor or in the slots of any similar stationary core member, clamps 63 will be so adjusted on the rods 23 and 24 that the coil ends will be forced outwardly from the center of the shaft 8. But, if the coils are intended for insertion in the slots formed in the convex cylindrical surface of a core member, such as a rotor, the clamps will be so adjusted that the coil ends will be pulled inwardly toward the center of the shaft 8. By this means, the ends of the coil are properly offset in every case to clear the opposed member when they are assembled in a dynamo-electric machine.

While the apparatus here shown and described has been found to be well adapted for the service intended, it will be understood that variations of structural details and arrangements of parts may be made without departing from the spirit and scope of my invention.

I claim as my invention:

1. A coil former comprising relatively movable hinge-connected members, side clamps adjustably secured to the respective members, pivotally mounted end clamps which are independently adjustable relative to the hinge-connected members, and means for adjusting one of said side clamps transversely of the member to which it is secured.

2. A coil former comprising a vertical plate or frame, a lever pivotally connected thereto, side clamps one of which is supported on the plate or frame and the other of which is both longitudinally and transversely adjustable relative to the lever, and end clamps independently adjustable relative to the hinge-connected members.

3. A coil former comprising a vertical plate or frame, a casting or bracket secured thereto, a lever pivotally secured to the casting or bracket, side clamp members adjustably secured to the plate or frame and to the lever, opposing end clamps pivotally and adjustably supported at the pivotal axis of the lever, and means for adjusting one of the side clamps transversely of the member on which it is mounted.

4. A coil former comprising relatively movable hinge-connected members, a side clamp adjustably secured to one of the members, a carriage adjustably secured to the other member, a second side clamp mounted on the carriage and transversely adjustable thereon relative to the member on which it is mounted.

5. A coil former comprising relatively movable hinge-connected members, a side clamp adjustably secured to one of the mem-

bers, a carriage block adjustably secured to the other member, a second side clamp mounted on the carriage and transversely adjustable thereon relative to the member on which it is mounted and end clamps independently adjustable relative to the hinge-connected members.

6. A coil former comprising relatively movable hinge-connected members, a clamp 10 adjustably secured to one of the members, a carriage adjustably secured to the other

member, a second clamp mounted on the carriage and transversely adjustable thereon relative to the member on which it is mounted.

In testimony whereof, I have hereunto 15 subscribed my name this 18 day of January, 1912.

MICHAEL SANDFIELD.
